UNITED STATES PATENT OFFICE.

CHARLES LAMBIE AND FREDERICK W. LAMBIE, OF MINNEAPOLIS, MINNESOTA.

CONVERTIBLE COT AND TABLE.

Application filed December 13, 1920. Serial No. 430,233.

To all whom it may concern:

Be it known that we, CHARLES LAMBIE and FREDERICK W. LAMBIE, citizens of the United States, residing at Minneapolis, in the county of Hennepin and State of Minnesota, have invented new and useful Improvements in Convertible Cots and Tables, of which the following is a specification.

This invention relates to collapsible or convertible furniture adapted for use in camping and the like, and has for its object the provision of a collapsible convertible cot or bed and table designed primarily for use by motorists and intended when not in use to be contained entirely within an enclosing box secured upon the running board of an automobile whereby the device will be fully protected against dirt and the effects of the weather.

An important object is the provision of a device of this character which includes a main supporting portion of a spring-like formation similar to some types of bed springs and adapted to be covered with a sheet of canvas to form a table, the invention further contemplating the provision of a mattress or other suitable bedding disposable upon the main platform or support to constitute a bed.

Another object is the provision of a device of this character which is provided with a collapsible top similar in construction to an automobile top for protecting the table in inclement weather and also for protecting the device in its capacity as a bed, this top having side curtains associated therewith to form a complete enclosure when the bed is occupied, the entire top structure being collapsible and designed to be stored between the box and the body of the automobile and to be strapped in place.

An additional object is the provision of a device of this character which will be simple and inexpensive in construction, easy to set up or take down, efficient in use, durable in service, and a general improvement in the art.

With the above and other objects and advantages in view, the invention consists in the details of construction to be hereinafter more fully described and claimed and illustrated in the accompanying drawings in which—

Figure 1 is a perspective view of the en-

closing box showing its position upon the running board of an automobile.

Figure 2 is a plan view showing the box open and our device in extended position,

Figure 3 is a side elevation of the device equipped with top and side curtains,

Figure 4 is a longitudinal sectional view therethrough showing the arrangement for the table,

Figure 5 is an end view,

Figure 6, is a side elevation of the device with portions broken away and in sections and showing the side curtains removed,

Figure 7 is a perspective detail view of one corner of one of the supporting posts,

Figure 8 is a perspective detail view of one end of one of the side bars.

Figure 9, is a cross sectional view showing the top supporting means,

Figures 10, 11 and 12 are detail views.

Referring more particularly to the drawings, the letter A designates a portion of an automobile and B designates the running board thereof. In carrying out the invention, we provide a rectangular box 10 formed of suitable material such as pressed steel and preferably enameled to match the automobile upon which it is used. This box has a hinged cover 11 equipped with a suitable lock 12. The box is mounted upon the running board B and is held thereon by means of suitable clamps 13 carried by a box and engaging the running board. It will be observed that there is a space between the back of the box and the body of the automobile and this space is utilized, as will be hereinafter explained.

The frame of the convertible bed and table comprises side bars 14 formed of a plurality of slidably connected sections 15. Each section has a slot 16 within which is slidably engaged a bolt 17 carried by the next adjacent section and this constitutes the slidably adjustable connection. The bolts 17 are provided with suitable nuts 18 which may be tightened to lock the parts against movement. The sides 14 support the bottom which is formed of diagonally arranged intersecting spring strips 18 which constitute a lazy tongs construction and which permit collapsing or extending of the side sections. One end section of each side is formed with a socket 20 engage-

able with a hook 19 carried by the box 10 so that this end of the frame may be supported. The other endmost section of each side is provided with an extension 20' having an enlarged head 21.

The outer end of the frame is formed by a transverse bar 22 formed of slidably connected sections, the sections being connected by bolts 23 passing through slots similar to 10 the elements 16 and 17. At their ends the sections carry castings 24 provided with recesses 25 having constructed entrances 26 within which the headed extensions 21 are engaged, this construction being the same 15 as that employed for connecting the side rails of metal beds with the corner posts. Carried by these end castings 24 are vertically adjustable legs 27 of telescopic construction and these legs are connected by 20 braces 28 with the central portion of the end 22. Intermediate of their ends the sides 14 carry slidably connected bar sections 29 at the ends of which are provided telescopic legs 30 similar to the legs 27 for the purpose 5 of supporting the intermediate portion of the frame.

Ordinarily, the various parts of the device are entirely disassembled and are simply packed within the box 10 which is 30 mounted upon the running board of the automobile. When the use of the device is desired, the operator or operators open the box, remove the various bars and other elements therefrom and then assemble the side bars by bolting them together with the bolts 17 which pass through the elongated slot 16. The ends of the side bars thus assembled, which ends are provided with the holes 20, are then engaged over the hooks 40 19 and the end members 22 which are connected by the bolt 23 are associated with the other end of the side bars by engaging the grooves at the ends of the end members upon the dove-tailed tongues at the 45 outer end of the side bars. The legs, which ordinarily are slid together as closely as possible whereby to occupy but little space, are then extended and clamped in the desired position by means of the bolts which 50 pass through the elongated slots therein. The sections of the central reinforcing bar 29 are assembled and this reinforcing bar is then associated with the side bars and its legs 30 are likewise adjusted to the same 55 height as the legs 27. The lazy tong bottom structure which is connected with the assembled end bar 22 is then stretched out with its sides resting upon the top of the side bars and with its opposite end resting 60 upon the forward end of the box 10. When desired, the covering is pulled from the roller 31 and hooked down over the end bars 22.

In order that the device may be used as 65 a table when it is in its extended position

of course, we provide a spring roller 31 mounted at the end of the frame adjacent the box 10 and having wound thereon a sheet of canvas 32 which is designed to be drawn off the roller and along the frame 70 to have its free end hooked upon the end member 22, as by means of suitable eyelets or other securing means. When the device is to be used as a bed this canvas is rolled up on the roller 31 and a pneumatic or other mattress is placed upon the frame, together 75 of course with any other desired bedding.

In order to provide protection against snow or inclement weather, we provide a canvas or top which comprises a plurality 80 of vertical rods 33 secured at the corners of the box 10, as by fitting within suitable sockets 34 and these rods are connected by a foldable brace rod 35. Incidentally these rods 33 are telescopic so that they may be 85 collapsed for convenience in storage. Secured upon opposite sides of the frame are sockets 36 within which are engaged upright rods 37 which are also telescopic and which are connected by a cross rod 38. Cross rods 39 likewise connect the upper ends of the pairs of rods 33. The top or canopy is completed by the canvas cover 40 which is connected with the cross bar 39 nearest the automobile body and which is stretched 90 tightly over the cross rods 39 and 38 and which has its free end brought down and secured to the end bar 22, as shown at 41. This canvas may be used when the device is employed as a table but it is designed primarily for use when the device is used as a bed. As a further protection against inclement weather we provide suitable side curtains 42 suitably connected with the top and with the sides 15 of the frame, the 100 connection being effected by means of the usual eyelets and turn buttons such as are employed on automobile tops and side curtains. It is of course to be understood that in fair weather these side curtains may be 110 replaced by other curtains made of netting to exclude flies and other insects.

When the device is used as a bed it is noted that the intended user may disrobe in the automobile and upon opening the door 115 thereof pass directly into the bed beneath the collapsible top thereof, the box 10, which of course must be previously closed, serving as a step. The width of the bed will of course depend upon the length of 120 the running board of the vehicle to which it is attached.

When the use of a canopy is not desired it is detached and rolled up with the various rods thereof rolled within the fabric cover 125 and the resultant bundle is disposed between the box 10 and the body of the car and secured against loss by means of suitable straps 42 secured to the box and carrying buckles. It is of course apparent that 130

when use of the device is not desired at all the sectional sides, cross members and telescopic legs are all collapsed and the various parts are stored within the box 10.

5 From the foregoing description and a study of the drawings it will be apparent that we have thus provided a simple and easily set up or taken down collapsible structure capable of use for the purpose specified 10 and of great advantage to motorists, picnickers or others finding it necessary to provide sleeping accommodations by the roadside.

While we have shown and described the 15 preferred embodiment of our invention, it is of course to be understood that we reserve the right to make such changes in the form, construction, and arrangement of parts as will not depart from the spirit of 20 the invention or the scope of the subjoined claims.

Having thus described our invention, we claim:

1. A device of the character described 25 comprising an enclosing box adapted to be clamped upon the running board of an automobile, a collapsible supporting frame normally disposed within said box and formed of a plurality of adjustably connected sections, a collapsible bottom member of lazy 30 tong formation adapted to rest upon the supporting frame when assembled, in combination with a canopy structure including pairs of slidably adjustable uprights adapt- 35 ed for association with the ends of the box,

the ends of the box being provided with sockets receiving said uprights, slidably adjustable inclined brace bars pivotally connected with said uprights, socket members formed on the intermediate portions of the 40 side bars of the supporting frame, a vertical adjustable inverted U-shaped arch having lower ends of its arms detachably engageable with said second named socket, and a cover connected with the upper ends 45 of said first named pairs of uprights stretched over said last named uprights and detachably connected with the end bar of the frame.

2. A device of the character described 50 comprising an enclosing box adapted to be clamped upon the running board of a vehicle, a frame formed of a plurality of slidably connected sections collapsible for disposition within said box and having one end 55 detachably connected with the box, supporting feet at the other end of the frame, a collapsible bottom of lazy tong formation disposable upon the frame and adapted to support a mattress to serve as a bed or 60 being adapted for use as a table, a spring roller at one end of said frame, and a sheet of canvas carried by said roller and adapted to be secured at the opposite end of the frame to form a cover therefor when used 65 as a table.

In testimony whereof we affix our signatures.

CHARLES LAMBIE.
FREDERICK W. LAMBIE.
